UNITED STATES PATENT OFFICE

2,527,035

CONCRETE ROOF

Roy William Rumble, Pretoria, Transvaal,
Union of South AfricaApplication April 11, 1947, Serial No. 740,903
In the Union of South Africa April 16, 1946

6 Claims. (Cl. 108—1)

1

This invention relates to roofs comprising a base and a roof slab; the roof slab being spaced above and connected to the base by vertically extending structure extending between them; and said base and roof slab being moulded in position from material that is moulded in a plastic condition, and being then caused or allowed to set, becomes solid building material. Such material is herein referred to as concrete.

In my prior patent application Ser. No. 599,427, I have described a roof of this class in which both the base and the roof slab are moulded in position from plastic concrete and the vertically extending structure is also moulded in position.

According to this invention in a roof of the kind described in the last paragraph but one, the vertically extending structure is pre-formed and its lower and upper ends are incorporated in the base and roof slab respectively when said base and roof slab are moulded.

The aforesaid base is a structure resting on the walls or wall equivalents and having mainly horizontal extension. It is either a solid slab; or the equivalent of a solid slab modified by aperturing such that the supporting properties of a solid slab in respect of the vertically extending structure are preserved; for example a group of horizontal beams.

In the case of a flat roof it is convenient to make the general plane of the roof slab parallel to the general plane of the base; but in a pitched roof the roof slab is inclined to the horizontal.

Regarding the nature of the vertically-extending structure, said structure comprises a number of metal rods spaced horizontally from one another and extending between the base and the roof slab with their individual ends incorporated by moulding into the material of said base and roof slab.

The rods are each bent alternatively back and forth in a single plane to zigzag shape and arranged vertically.

The legs formed by bending the rods are either progressively shorter from the centre of each rod outwards, with the upper bends to each side of the centre in a straight line with one another to form a unit which is triangular in side view and therefore conforms with the cross-sectional shape of a pitch roof; or the legs are of equal length for use in a roof in which the base and the roof slab are parallel.

In either case, the base and the roof slab may be spaced vertically apart at least at those edges of the base which are transverse to the extent

of the rods, and the roof slab may project beyond those edges to form overhanging eaves.

The rods are preferably such as are easily and cheaply available, and readily bendable; concrete reinforcing rod being particularly suitable.

The general nature of the vertically-extending structure is such that there may be detachably or displaceably secured to it means, such as cleats, suitable to support shuttering for moulding the roof slab, the method of support being such that said shuttering may be lowered away from the set roof slab after the removal or displacement of said means.

The invention is illustrated by the examples shown in the accompanying drawings, in which—

Figure I is a perspective view of a pitched roof in several stages of construction.

Figures II and III are perspective views of other forms of a pitched roof.

Figure IV is a perspective view of a flat roof. Figure I shows a roof comprising a ceiling slab 2 carried by side walls 3, and the roof slab 4; both slabs 2 and 4 being moulded in situ.

The shuttering for the ceiling slab is that described in my prior patent application Serial No. 599,427. Cross girders 5 of T section are temporarily supported by their ends 6 being received into gaps 7 formed on the tops of the walls 3 and resting on removable blocks or wedges 8. Brackets 9 are removably secured to the inside face of the gable walls 10. Shuttering panels 11 forming a temporary floor are laid on said girders and brackets and the ceiling slab 2 is cast on said floor and over the tops of the walls 3. A metal mat 12 is usually laid down so as to become incorporated in the set concrete. When the slab 2 has set, the brackets 9 are removed. The blocks or wedges 8 are also removed, allowing the girders 5 and panels 11 to drop clear of the moulded ceiling slab 2. The girders 5 are withdrawn endwise; allowing the panels to be taken down. This shuttering system forms no part of the present invention.

According to the invention, there is provided a number of the units 13 of the vertically extending structure. Each is made of concrete-reinforcing bar, bent back and forth to form a number of legs 14 united to one another by the bends 15, 15a at their ends. Moreover the legs 14 are of graded lengths to make the profile of the unit similar to the cross section of the roof structure. That is to say, the lower bends 15a are arranged in a horizontal line 16 corresponding to the transverse section of the roof slab, whilst the legs increase in length from both ends

of the unit to its centre, bringing the upper bends 15 into two lines 17 and 18 sloping upward from their ends to meet one another at the point 19 corresponding to the ridge of the roof. This device provides both vertical support and diagonal bracing.

After the mat 12 has been laid, and before the ceiling slab 2 is poured, a number of the units 13 are stood upright on the mat 12, like roof trusses, and their lower bends 15a are tied to the mat 12 by ties 20. They are temporarily supported and the ceiling slab 2 is then so poured that the mat 12 and the lower bends 15a become incorporated in it. The units 13 become self-standing when the slab 2 has set as appears at the right hand end of Figure I.

The next step uses the self-standing units 13 to support the shuttering for the roof slab. Pairs of cleats 21, 22 are provided; one being placed at each side of a pair of legs 14, 14 meeting at the upper bend 15, near to the latter; and the pair of cleats 21, 22 is clamped to the legs 14, 14 by a through bolt 23. Shuttering panels 24 are rested on the clamped cleats 21, 22 and are so positioned relatively to the upper bends 15 that the latter extend above them to a proper height to be incorporated into the slab cast on the shuttering panels.

The gaps 25 between the panel edges 26 caused by the legs 14 coming between them are covered by thin slips 27. Shuttering pieces 28 to mould the edges of the eaves are put into position, as is also a reinforcing mat 29 which is tied to the upper bends 15. The roof slab 4 is then cast on the shuttering 30; incorporating said mat 29 and said upper bends 15 into itself. The pairs of cleats 21, 22 are then loosened and removed by a workman inside the roof and the panels 30 (and slips 27) are withdrawn. They are conveniently withdrawn through an open gap 31 between the ceiling slab 2 and the roof slab 4, as indicated by the arrow A; said gap 31 being conveniently left to provide ventilation of the roof cavity 32 and being protected by the roof slab 4 being extended as an overhanging eaves 33.

Figure II shows a roof structure similar to that of Figure I, but in which the ceiling slab 2 is omitted and its place taken by a series of cross beams 34. In the case of an open-sided building said beams 34 rest on separate pillars 35. The beams are moulded to incorporate the lower bends 15a of the units 13; and the procedure thereafter may be that described in connection with Figure I except that the absence of a ceiling simplifies the removal of the shuttering from the roof cavity 32a. In the completed roof the roof slab 4a provides a rigid connection between the initially separate pillar and beam units.

Figure III shows another form of pitched roof in which the units 13a extend parallel with the ridge 36. In that case said units 13a are of uniform height along its length and the several units on either side of the ridge diminish successively in height. This form may be combined with the Figure I form; providing diagonal bracing of the roof in two directions.

Figure IV shows a flat roof 4b with the flat ceiling slab 2a and flat roof slab spaced apart by a few inches, forming in effect one hollow slab; the reinforcement units 13b being of cor-

responding uniform and low height. In erecting this roof the units 13b are moulded into the ceiling slab 2a as in the first example. Owing to the small and uniform distance separating the slabs 4b and 2a, it is convenient to use a number of devices 37 in the nature of expansible cores which are laid on the formed ceiling slab 2a and provide an upper surface 28 on which the roof slab 4b is cast in a position to incorporate into itself the upper bends 15 of the units 13b; said devices 37 being such or so supported that their upper moulding surface 38 can be lowered from under the formed roof slab 4b so that the latter remains supported on the units 13b.

I claim:

1. A roof comprising a base as herein defined and a roof slab, the base and the slab being spaced vertically apart and both base and roof slab being of concrete, and comprising also a number of metal rods each bent alternately back and forth in a single plane to zig-zag shape and arranged vertically with the lower bends incorporated in the material of the base and the upper ends incorporated in the material of the roof slab, the various rods being arranged parallel with each other and spaced horizontally apart and being continuous across the roof.

2. The roof claimed in claim 1 of gable shape in which with respect to each rod the legs resulting from bending the rod to zig-zag shape are progressively shorter from the centre of the rod outwards, with the upper bends to each side of the centre in a straight line with each other to form a unit which is triangular in side view.

3. The roof claimed in claim 1 in which the roof slab and the base are parallel and in which, with respect to each rod, the legs are of equal length, with the upper and lower bends in straight lines with each other, the lines being parallel.

4. The roof claimed in claim 1 in which the rods are concrete-reinforcing bars.

5. A roof comprising a base as herein defined and a roof slab, both base and roof slab being of concrete, and comprising also a number of metal rods each bent alternately back and forth in a single plane to zig-zag shape and arranged vertically with the lower bends incorporated in the material of the base and the upper ends incorporated in the material of the roof slab, the various rods being arranged parallel with each other and spaced horizontally apart, and being continuous across the roof; the base and the roof slab being spaced vertically apart and the roof slab projecting beyond the base to form overhanging eaves at least at the edges of the slab which are spaced from the roof slab.

6. The roof claimed in claim 5 in which the rods are concrete-reinforcing bars.

ROY WILLIAM RUMBLE.
